FIG. 1

FIG. 2

FIG. 3

FIG. 4

FIG. 5

FIG. 1 is a perspective view of my grinding wheel incorporating my invention;

FIG. 2 is a front view of the grinding wheel depicted in FIG. 1;

FIG. 3 is a rear view of the grinding wheel depicted in FIG. 2;

FIG. 4 is a side view of the grinding wheel depicted in FIG. 2 as viewed from the left thereof with the opposite side being identical to the side shown; and

FIG. 5 is a top plan view of the grinding wheel depicted in FIG. 2, with the opposite bottom portion thereof identical to the top portion shown.

The intermediate ring shown in the drawing is markedly visible and immediately perceptible to the eye of the observer owing to the difference of the material of the intermediate ring with regard to the adjacent rings.

I claim:

The ornamental design for a grinding wheel or similar article, as shown and described.
